GARMENT

William Daniel, Brooklyn, N. Y., assignor to
Greenhill & Daniel, Inc., Brooklyn, N. Y., a corporation of New York

Application November 6, 1934, Serial No. 751,720

2 Claims. (Cl. 2—224)

My invention relates to a new and improved garment.

One of the objects of my invention is to provide improved bathing suit trunks.

5 Another object of my invention is to provide an improved waist construction for a nether garment, such as bathing suit trunks or the like.

Another object of my invention is to provide an improved belt construction for a nether garment such as bathing suit trunks and the like.

10 Another object of my invention is to provide a belt construction which shall be efficient and which shall have an ornamental appearance, said belt construction comprising a plurality of 15 guide members together with belt loops.

Other objects of my invention will be set forth in the following description and drawing which illustrates a preferred embodiment thereof, it being understood that the above statements of 20 the objects of my invention are intended to generally explain the same without limiting it in any manner.

Fig. 1 is a front elevation of the improved garment.

25 Fig. 2 is a rear elevation of Fig. 1.

Fig. 3 is a top plan view.

Fig. 4 is an enlarged detail front elevation of the garment, the belt having been removed.

The garment generally comprises a front part 30 and a rear part and it is formed with leg members 1 and 2. The body of the garment is made in any suitable manner.

The lower edges of the leg portions are inturned and said inturned portions are connected to the 35 body of the garment by means of stitches 3 and 3a.

Each wall of the garment is also provided with 40 vertical lines of stitches 4 and 4a. Said lines of stitches are visible at the exterior of the front wall and of the rear wall of the garment. At the inside surface of the front wall, and at the inside surface of the rear wall, said stitches are connected by transverse loops, which are of the type of the loops L shown in Fig. 4.

45 The crotch of the garment extends up to the point 6.

In this construction the garment is made up of 50 two pieces of fabric A and B, and these two pieces of fabric have their edges inturned, said edges are connected by through-and-through stitches, and the garment is then finished by the lines of stitches 4 and 4a and the loops L.

The side seams of the garment are formed 55 by the lines of stitches 8 and 8a, these being con-

nected at the inner surfaces of the garment by loops L.

As shown for example in Fig. 4, the upper end of the garment has its edge turned downwardly and a part of said downwardly turned edge portion is connected to the body of the garment by means of lines of stitches 14 and 14a, these being connected by loops L at the inner surface of the garment.

As shown in detail in Fig. 4, the front wall of 10 the garment is formed with two concave recesses. A portion of the upper edge of the garment is downwardly turned so as to form a tab 15, by means of which a ring 16 is connected to this portion of the garment.

The upper edges of the garment are downwardly turned and finished as previously mentioned, before the tab 15 is formed, by downwardly turning a portion of the upper edge of the garment.

The ring 16 is made of metal or celluloid or any other suitable material, and it can be turned in its own plane relative to the garment, as the connection which is provided by the tab 15 is sufficiently loose for this purpose.

After part of the upper edge of the garment has been finished by means of the stitches 14 and 14a, the corners of the front of the upper edge of the garment are turned laterally, in order to form tabs 17 and 17a. The edges of said tabs 30 15 and 17 and 17a are stitched to the body of the garment.

A ring 18 is held in position by means of the tab 17, and a ring 18a is held in position by means of the tab 17a. Said rings 18 and 18a are also 35 turnable since they are connected loosely to the garment.

In this particular embodiment the belt member H is made of a cord, but said belt member could be of any type or shape.

In this embodiment I have shown two separate belt members.

As shown in Fig. 3, the rear wall of the garment is provided with a plurality of belt loops 20 and any desired number of belt loops could 45 be utilized.

Referring to each of the belt members H, this is passed through a loop 20, then through the ring 16, then through and around the ring 18, back through the ring 16, and back through the 50 same loop 20. The belt member is therefore formed into a loop, the end of said loop being around the wall of the ring 18. The outer ends of the two belt members are then tied together or secured in any suitable manner if desired. 55

After the garment has been put on, the belt members can be tied or connected in any suitable manner at the rear of the garment.

The rings 18 and 18a are preferably smaller than the ring 16 and said rings 18 and 18a can be made of any suitable material, either rigid or non-rigid. Likewise the ring 16 could be made of non-rigid material if desired.

While I have shown ring-shaped members 16, 18 and 18a, these may be of any form. The garment may be made of any suitable knitted or woven material, said material preferably having a certain longitudinal elasticity and having a much greater transverse elasticity.

The belt loops 20 have their upper ends connected to the waist portion of the garment at about the level of the lines of stitches 30 and 30a. Said lines of stitches 30 and 30a connect part of the inturned upper edge of the garment to the body thereof. Additional stitches 40 and 40a may be used for connecting the loops 20 to the rear wall of the garment.

While I have specified that the eye-members or rings are located at the front of the garment, it would not be departing from the invention if this relationship were reversed and said eye-members were located at the rear wall of the garment.

I have shown a preferred embodiment of my invention, but it is clear that numerous changes and omissions can be made without departing from its spirit.

I claim:

1. A garment of the class described having a waist portion, said waist portion being provided with an eye-member at the front wall thereof, said waist portion also having additional eye-members located at each side of the first mentioned eye-member, said garment having a pair of loop-shaped belt members, each said loop-shaped belt member passing through and around one of said additional eye-members so that the wall of said eye-member is between the two parts of the loop and said additional eye-member serves to anchor the inner end of said loop, said belt-member also passing slidably through the first mentioned eye-member.

2. A garment of the class described having a waist portion, said waist portion being provided with an eye-member at the front wall thereof, said waist portion also having additional eye-members located at each side of the first mentioned eye-member, said garment having a pair of loop-shaped belt members, each said loop-shaped belt member passing through and around one of said additional eye-members so that the wall of said eye-member is between the two parts of the loop and said additional eye-member serves to anchor the inner end of said loop, said belt-member also passing slidably through the first mentioned eye-member, said garment also having a belt loop at the rear wall of the waist portion thereof, and through which the belt member passes.

WILLIAM DANIEL.
